United States Patent Office.

MICHAEL TROMLY, OF CINCINNATI, OHIO, ASSIGNOR TO HIMSELF AND W. L. HASBROUCK, OF SAME PLACE.

Letters Patent No. 100,217, dated February 22, 1870.

IMPROVEMENT IN ESCAPEMENT FOR TIME-PIECES.

The Schedule referred to in these Letters Patent and making part of the same.

To all whom it may concern:

Be it known that I, MICHAEL TROMLY, of Cincinnati, in the county of Hamilton, and State of Ohio, have invented a new and useful Improvement in Clocks; and I do hereby declare that the following is a full, clear, and exact description of the construction and operation of the same, reference being had to the accompanying drawings making part of this specification, in which—

My invention is represented by a front elevation of a clock with the upper portion of the front plate removed so as to show the striking-wheel and the lifter on the minute shaft, and a detached view of the escapement.

This invention consists in a new escapement, the same being made up of a single pallet provided with a wire arm connected at its free end with a cam groove on the hub of the balance-wheel, in such manner that at each vibration of the latter the pallet is thrown out to allow one tooth to pass.

In the drawings—

A is the striking-wheel, having seventy-eight teeth, a, in its perimeter, each tooth acting on the hammer a', so as to produce a stroke upon the bell a''.

On one side of the wheel A is a series of thirteen pins b, arranged near the rim in a circle, the spaces between said pins representing an arithmetical progression of twelve terms with a constant difference of one.

Motion is communicated to the wheel A by a spring, b', coiled around its shaft in the usual manner.

The pins, in their orbit, come in contact successively with a stop, c, having a slot, c', in it for the pins to slip through on the lowering of the stop by the eccentric lifter c" on the minute shaft c'" at the moments for striking the hours.

On the passage of one of the pins through the slot c', the lifter having passed, the stop immediately resumes its former position so as to be ready to intercept the next pin, which strikes the stop in no longer time than is required to strike the hour, and is in its turn let through when its hour arrives. The wheel A makes but two revolutions in twenty-four hours.

For striking the half hour, I attach another eccentric lifter to the minute shaft, which raises a hammer and lets it fall upon the bell at one half past without being in connection with any other gearing.

I construct the balance-wheel B of about thrice the usual diameter of balance-wheels, but of the same weight, in order to treble the momentum and proportionately diminish friction. By this arrangement I am enabled to run a balance-wheel clock with as little waste of power as a pendulum.

The escapement consists of a single pallet, d, pivoted at d', and having an arm, d'', extending from its rear and lower part into the cam-groove d' on the shaft of the balance-wheel.

The hub of the balance-wheel bears a pin, x, which forms the other tooth of the escapement. Thus every vibration of the balance-wheel withdraws the detent from its cog-wheel and restores it, with unfailing accuracy, allowing one tooth to escape meanwhile.

Having thus described my invention,

What I claim as new, and desire to secure by Letters Patent, is—

The pallet d, combined with the arm d'', pin x, and cam-groove d', as and for the purpose set forth.

MICHAEL TROMLY.
